US00D571457S

(12) **United States Design Patent**
Dolezal et al.

(10) **Patent No.:** **US D571,457 S**
(45) **Date of Patent:** **** Jun. 17, 2008**

(54) **BREATHING AIR FILTRATION DEVICE**

(75) Inventors: **David M. Dolezal**, Edina, MN (US);
John D. Wilder, Brooklyn Park, MN
(US); **Daniel M. Gelfman**, Minnetonka,
MN (US)

(73) Assignee: **Dolezal Creative Innovations, LLC**,
Edina, MN (US)

(**) Term: **14 Years**

(21) Appl. No.: **29/239,438**

(22) Filed: **Sep. 29, 2005**

(57) **CLAIM**

The ornamental design for a breathing air filtration device, as shown.

DESCRIPTION

FIG. 1 is a perspective view of a breathing air filtration device showing our new design;

FIG. 2 is a top view thereof;

FIG. 3 is a front view thereof;

FIG. 4 is a right side view thereof;

FIG. 5 is a left side view thereof;

FIG. 6 is a rear view thereof; and,

FIG. 7 is a bottom view thereof.

1 Claim, 3 Drawing Sheets

UNITED STATES PATENT AND TRADEMARK OFFICE
CERTIFICATE OF CORRECTION

PATENT NO. : Des. 571,457 S

Page 1 of 1

APPLICATION NO. : 29/239438

DATED : June 17, 2008

INVENTOR(S) : David M. Dolezal, John D. Wilder and Daniel M. Gelfman

It is certified that error appears in the above-identified patent and that said Letters Patent is hereby corrected as shown below:
